UNITED STATES PATENT OFFICE.

FRANCIS J. LAPOINTE, OF ANN ARBOR, MICHIGAN.

MILK-BOTTLE COVER AND CAP REMOVER.

1,426,396.

Specification of Letters Patent. Patented Aug. 22, 1922.

Application filed March 28, 1921. Serial No. 456,462.

To all whom it may concern:

Be it known that I, FRANCIS J. LAPOINTE, a citizen of the United States of America, and a resident of Ann Arbor, in the county 5 of Washtenaw and State of Michigan, have invented certain new and useful Improvements in Milk-Bottle Covers and Cap Removers, of which the following is a specification.

10 This invention relates to closures and cap removers for milk bottles and the like and has for its object the provision of a combined cover and cap remover.

The invention consists primarily in a 15 cover having a corrugated apron depending therefrom and adapted to surround the top of the bottle, said cover having struck therefrom two prongs bent angularly to said cover so that in the rotation of the cover relatively to the bottle, the prongs will pierce

20 the paper cap and insure its removal from the bottle when the cover is lifted from the bottle.

The invention further consists in providing means for ejecting the cap from the prongs when said cap has been removed from the bottle.

The invention further consists in certain 30 novel features of construction and arrangement of parts which will be understood readily by reference to the description of the drawings and to the claims to be hereinafter given.

For the purpose of illustrating the invention, one preferred form thereof is illustrated in the drawings, this form having been found to give satisfactory and reliable results although it is to be understood that the various instrumentalities of which the 35 invention consists can be variously arranged and organized and the invention is not limited to the precise arrangement and organization of these instrumentalities as herein shown and described except as required by 40 the scope of the appended claims.

Of the drawings:

Figure 1 represents a plan of a bottle cover embodying the principles of the present invention.

50 Figure 2 represents a section of same on line 2, 2, on Fig. 1.

Figure 3 represents an inverted plan of the same, and

55 Figure 4 represents a vertical section of the same showing a portion of a milk bottle and the prongs of the cover engaging the

paper cap thereof preparatory to its removal from the bottle.

Similar characters indicate like parts throughout the several figures of the drawings.

In the drawings, 10 is a top of a milk bottle of usual construction having a paper cap 11 disposed in the opening thereof.

12 is a cover adapted to be placed upon 65 the top of the bottle and having a depending apron 13 adapted to surround the top of a bottle.

This apron 13 is corrugated as indicated in the drawings whereby the operator is 70 enabled to secure a firm hold on the cover when it is desired to rotate the same about its center for the purpose of removing the paper cap from the bottle.

The cover is provided with a plurality of 75 sharply pointed prongs 14 which are preferably struck from said cover and are bent downwardly at an angle to the under surface thereof.

These prongs are preferably curved about 80 the center of the cover as indicated in Fig. 3 of the drawings.

When the cover is pressed down over the top of the bottle and rotated, the prongs 14 will pierce the cap 11 as shown in Fig. 4 85 of the drawings.

This piercing of the cap having been accomplished, the lifting of the cover from the bottle will remove the paper cap 11 therefrom.

90 Centrally disposed relatively to said cover 12 is a reciprocating member 15 having a head 16 and provided with a disk-like portion 17 between the prongs 14.

The disk-like portion 17 is preferably provided with a shank 18 having a reduced end 19 extending into the member 15 and secured thereto by means of a pin 20.

Between the lower end of the member 15 and the upper end of the shank 18 is a plate 100 21 which normally covers the openings in the cover 12 caused by the formation of the prongs 14 struck from said cover.

The normal position of the various parts are as shown in Fig. 2 of the drawings and 105 when the cap has been removed from the bottle 10 and the cover is in position thereon, the various parts of the cover are in the position shown in said Fig. 2.

When a fresh bottle of milk is received 110 and it is desired to remove the paper cap therefrom, the cover 12 is placed upon the

upper end of the bottle 10 and as soon as the disk 17 comes into contact with the paper cap 11, the member 15 is moved upwardly into the position indicated in Fig. 5 4 of the drawings.

The prongs 14 in the meantime, by the rotation of said cover, have pierced the paper cap in an obvious manner, pressure on the head 16 preventing the rotation of 10 the paper disk 11 during the rotation of the cover 12.

As soon as the cover 12 has been lifted from the bottle with the cap 11 on the 15 prongs 14, it is desirable to remove the cap from the cover before replacing the cover on the bottle.

This is easily accomplished by depressing the member 15 by applying a finger to the head 16 and pressing downwardly thereon.

20 This action will force the cap from the prongs and then the cover is again placed upon the bottle with the plate 21 covering the openings in said cover.

By providing a means at the outer edge 25 of the cover whereby the entire cover is rotated in order to cause the engagement of the prongs 14 with the paper cap 11 while the rotation of the cap is prevented by the disk 17, a greater leverage is secured than 30 could be attained by the devices now in general use.

In most devices now in use, the engaging prongs are mounted on a central spindle having a small knurled head by which the 35 prongs are rotated in order to engage the paper cap.

Very little leverage is obtained by such a construction and as a consequence it is sometimes difficult to cause the prongs to 40 engage the paper cap in order that the same may be removed from the bottle.

None of the devices now in use as far as is known, are provided with a means whereby the paper cap may be ejected from 45 the prongs.

Heretofore it has been necessary to remove the cap from the prongs by hand which is obviously objectionable.

This makes a very simple construction 50 of cap remover for milk bottles which can

be utilized to cover the bottle after the cap has been removed therefrom.

It is believed that the operation and many advantages of the invention will be understood without further description. 55

Having thus described my invention, I claim—

1. In a device of the character described, a cover; cap-engaging prongs struck therefrom and disposed at an acute angle relatively to 60 the under surface thereof; a plate normally covering the openings made in said cover by the formation of said prongs; and means at the outer edge of said cover whereby it may be rotated about its center. 65

2. In a device of the character described, a cover; depending prongs struck therefrom and disposed at an acute angle to the under side thereof; and means carried by said cover and positioned between said 70 prongs for ejecting the paper cap from said prongs.

3. In a device of the character described, a cover rotatable about the top of a bottle having a paper cap; separated oppositely disposed depending prongs struck therefrom and disposed at an acute angle to the under side thereof; and a reciprocating member carried by and centrally disposed relatively to said cover having a disk the edge of which 75 is normally adjacent the inner edges of said prongs and the bottom of which normally rests upon the bottle cap, said disk being adapted to eject the paper cap from said prongs by downward pressure upon said 80 reciprocating member.

4. In a device of the character described, a cover rotatable about the top of a bottle having a paper cap; cap-engaging prongs on the under face thereof and angularly 90 disposed relatively thereto; and means carried by said cover adapted to be pressed against said cap to prevent its rotation during the rotation of said cover.

Signed by me at Ann Arbor, Mich., this 95
24 day of March, 1921.

FRANCIS J. LAPOINTE.

Witness:

DAVID A. DE LONG.
